[57] CLAIM

The ornamental design for a color printer for use with solid ink sticks, as shown and described.

DESCRIPTION

FIG. 1 is a front perspective view of the printer showing environmental features of the printer in dotted lines;

FIG. 2 is a top plan view thereof showing environmental features of the printer in dotted lines;

FIG. 3 is a right side elevational view thereof;

FIG. 4 is a left side elevational view thereof;

FIG. 5 is a front elevational view thereof showing environmental features of the printer in dotted lines;

FIG. 6 is a rear elevational view thereof;

FIG. 7 is a front perspective view of the printer of FIG. 1 with the environmental features removed;

FIG. 8 is a top plan view of the printer shown in FIG. 2 with the environmental features removed; and,

FIG. 9 is a front elevational view of the printer of FIG. 5 with the environmental features removed.

The broken lines in FIGS. 1, 2 and 5 are for purposes of illustration only and from no part of the claimed design.
